(57) **CLAIM**

The ornamental design for a hood connector, as shown and described.

DESCRIPTION

FIG. 1 is an upper right front axonometric view of a hood connector showing an alternative design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines in the drawings depict portions of the hood connector and form no part of the claim.
